UNITED STATES PATENT OFFICE.

HUGO LOEWENBACH, OF MILWAUKEE, WISCONSIN.

RECEIPT AND RECORD BOOK.

SPECIFICATION forming part of Letters Patent No. 390,087, dated September 25, 1888.

Application filed May 10, 1887. Serial No. 237,676. (No model.)

To all whom it may concern:

Be it known that I, HUGO LOEWENBACH, of Milwaukee, in the county of Milwaukee, and in the State of Wisconsin, have invented certain new and useful Improvements in Receipt and Record Books; and I do hereby declare that the following is a full, clear, and exact description thereof.

My invention relates to receipt and record books such as are used by merchants, manufacturers, and others in shipping freight and express matter, and will be more fully set forth hereinafter.

In the drawings, Figure 1 is a perspective view of one form of my present invention, which I term a "duplicate" book. Fig. 2 is a like view of another form of my said invention, which I term a "triplicate" book, with the sheets of carbon paper belonging thereto in place, both of said figures representing books from which the detachable leaves have been partly removed, and hence showing only the narrow permanent leaves at the left.

25 A represent the covers of a bound book, a certain number of the leaves C C of which are originally of substantially the entire width of the book; but said leaves, near where they are bound into the book, are divided vertically by a row of perforations, a, so as to leave a narrow strip, b, when one of these leaves C has been removed.

In the form of my device shown in Fig. 1 these detachable wide leaves C are alternated 35 with narrower leaves, B, permanently bound into the book and not detachable.

In the form of device shown in Fig. 2 a similar arrangement exists, except that between the first permanent narrow leaf B and first 40 wide detachable leaf C there is interposed a narrow detachable leaf, D, with a vertical row of perforations, c, dividing the main or detachable portion of said leaf D from its stub d, which latter is permanently bound into the book like the stub b of the wide detachable leaf C and the permanent leaf B, and this arrangement is continued throughout the entire book, and, besides this, some portion of the edge or one of the corners of the leaf B is cut 45 out or off, as shown at e, so that a portion of

each leaf D will be exposed when the corresponding leaf B is flat thereon, and this exposed portion (marked f) may have, if preferred, any suitable inscription (such as "Tear out") printed thereon, and a like inscription 55 may, if desired, be printed at any suitable place (as at the point marked g) on the leaf C. The upper portion of every leaf, above the line h, may be printed appropriately to order with the name and address of the user, while 60 below this line the items or other matter may be written, (on the permanent leaf B,) and if the carbon sheet or sheets E are in place then a duplicate (or triplicate) of this writing will appear upon the sheet C, or the sheets D and 65 C, (according to which book is used,) and these leaves may be torn out for obvious purposes.

My present invention is, in part, an improvement on that shown in my prior application for patent for "receipt and record books" filed 70 July 16, 1886, Serial No. 208,170, and its use and advantages are too obvious to require elaborate description.

Having thus fully described my invention, what I claim as new, and desire to secure by 75 Letters Patent, is—

1. A carbon copying receipt and record book consisting of a series of blank leaves of thin paper extending the entire width of the book, having between them one or more other 80 blank leaves of similar material of less width than the first-named leaves, substantially as and for the purpose set forth.

2. A carbon copying receipt and record book consisting of a series of blank leaves of thin paper extending the entire width of the book, having between each two of said wide 85 leaves two narrower blank leaves of similar material, one of said narrow leaves having a portion of its edge cut off or out, so as to expose part of the other narrow leaf, substantially as and for the purpose set forth.

3. A carbon copying receipt and record book consisting of a series of detachable blank leaves of thin paper extending the entire width 95 of the book, with two narrow blank leaves of similar material between each two wide leaves, one only of said narrow leaves being detachable, and the permanent leaves and stubs of the detachable leaves permanently bound be- 100

tween the covers of the book, substantially as and for the purpose set forth.

4. In a carbon copying receipt and record book, the combination of series of permanent and detachable leaves bound together, each of the former having a portion of its edge cut off or out, so as to expose part of the leaf below, substantially as and for the purpose set forth.

In testimony that I claim the foregoing I do have hereunto set my hand, at Milwaukee, in the county of Milwaukee and State of Wisconsin, in the presence of two witnesses.

HUGO LOEWENBACH.
